UNITED STATES PATENT OFFICE.

PHILIP RILEY, OF NEW BEDFORD, MASSACHUSETTS.

IMPROVED METHOD OF SECURING SHOE-TIPS.

Specification forming part of Letters Patent No. 59,656, dated November 13, 1866.

To all whom it may concern:

Be it known that I, PHILIP RILEY, of New Bedford, in the county of Bristol, in the State of Massachusetts, have invented a new and Improved Mode of Securing Tips to the Toes of Boots and Shoes; and I do hereby declare that the following is a full and exact description thereof, reference being had to the accompanying drawings, and to the letters of reference marked thereon.

My invention consists in sewing tips to the toes of boots and shoes by a loop-stitch, as herein shown.

Figure 1 is a perspective view of a shoe with a tip secured to it by my invention. Fig. 2 is a perspective view of the toe of a shoe with a tip partially secured to it. Fig. 3 is a tip, showing a loop-stitch around the margin of it.

In Fig. 1, A¹ is a shoe. B¹ is a tip sewed on the toe by the loop-stitch set forth in the within specification.

In Fig. 2, A² is the toe of a shoe. B² is a tip partially sewed onto the toe. a² a² a², &c., are loop-strokes set in the margin of the tip. b² b² are waxed threads by which the tip is sewed to the sole of the shoe.

In Fig. 3, B³ is a tip. a³ a³ a³, &c., are loop-strokes set in the margin of it.

The tips for the toes of boots and shoes being cut in suitable form, as shown by B³, (see Fig. 3,) with loop-strokes sewed around and in the margins, as shown by a³ a³ a³, &c., (see

Fig. 3,) the novelty of securing the tips may be noted.

The sole and upper leather being pressed apart by a blunt-edged tool, the tip is put on, and the waxed thread with which it is sewed is passed through the sole, and then through the first loop and sole and drawn tight, which turns in the edge of the tip and secures it to the shoe. Each successive loop is then sewed to the sole, giving the tip the appearance of having been "lasted in" when the shoe was made, and making it equally as durable.

I do not confine myself to a loop-stitch sewed around the margin of a tip, as a chain-stitch may be used, nor alone to putting on toe-tips, as my invention may be applied to heel tips or patches; neither do I claim any device previously invented or patented for securing tips to the toes of boots and shoes; but

What I claim as my invention, and desire to secure by Letters Patent, is—

Securing tips to the toes of boots and shoes by stitching around and through the margins of the tips a loop or chain stitch, and sewing the upper side of the loop or chain stitch to the sole, as herein set forth and described.

PHILIP ^{his} RILEY.
